UNITED STATES PATENT OFFICE.

EVELYN VAN NORMAN KRIEHN, OF NEW YORK, N. Y.

DESIGN FOR A BRUSH.

Application filed May 1, 1922. Serial No. 2,024. Term of patent 14 years.

To all whom it may concern:

Be it known that I, EVELYN VAN NORMAN KRIEHN, a citizen of the United States, residing in the borough of Manhattan, city of New York, county and State of New York, have invented a new, original, and ornamental Design for Brushes, of which the following is a specification, reference being had to the accompanying drawing, forming a part hereof.

Fig. 1 of the drawing is a top plan of a brush embodying my new design, and Fig. 2 is an elevation thereof, with one edge of the back broken away to show the configuration of the brush.

I claim:

The ornamental design for a brush as shown.

EVELYN VAN NORMAN KRIEHN.
